UNITED STATES PATENT OFFICE

118,665

DESIGN FOR A MERCHANTISING SACK OR SIMILAR CONTAINER

Hal K. Knowles and William Fleming,
New Orleans, La.

Application November 9, 1939, Serial No. 88,165

Term of patent 7 years

To all whom it may concern:

Be it known that we, Hal K. Knowles and William Fleming, citizens of the United States of America, residing at New Orleans, in the parish of Orleans and State of Louisiana, have invented a new, original, and ornamental Design for a Merchandising Sack or Similar Container, of which the following is a specification, reference being had to the accompanying drawing, forming a part thereof.

In the drawing:

Figure 2 is a rear view.

We claim:

The ornamental design for a merchandising sack or similar container, as shown.

HAL K. KNOWLES.
WILLIAM FLEMING.
